UNITED STATES PATENT OFFICE.

WILLIAM A. LEDDELL, OF DENVER, COLORADO, ASSIGNOR TO THE MINE AND SMELTER SUPPLY COMPANY, OF DENVER, COLORADO, A CORPORATION OF COLORADO.

METHOD OF MAKING GRATE-BARS.

1,398,492.

Specification of Letters Patent. Patented Nov. 29, 1921.

Application filed June 9, 1920. Serial No. 387,599.

To all whom it may concern:

Be it known that I, WILLIAM A. LEDDELL, a citizen of the United States, and a resident of Denver, county of Denver, and State of Colorado, have invented certain new and useful Improvements in Methods of Making Grate-Bars, of which the following is a specification.

My invention relates to the manufacture of grate bars by a method which possesses advantages as hereinafter pointed out over the methods now practised.

The grate bar to which this invention is directed is one in which one face of the bar is provided with spacing projections or pads for spacing the bars when they are assembled into grate form.

In this style of grate bar as now manufactured, the depth of the spacing-pads or projections on the face of the bar is necessarily limited owing to the method of manufacture employed and it is an object of the present invention to provide a method of manufacturing grate bars wherein these spacing-pads or projections may be made of any desired depth.

In the accompanying drawings,—

Figure 1 shows a partially finished grate bar in the form of a grizzly; Fig. 2 shows a finished grate bar in perspective;

Fig. 3 shows several bars assembled in a grate; and

Fig. 4 shows a grate structure made up of bars formed by my method, being a section on the line 4—4 of Fig. 3.

The blank from which the grizzly A of Fig. 1 is formed is first of all passed through a mill and rolled to form beveled faces B and C thereon, such as indicated in Fig. 2 for example. The bar is then subjected to pressure by passing the same through a suitable die press to cause a portion of the face thereof to be depressed out of the plane of the face C as indicated by D in Fig. 3 to form a tapered projection or spacing-pad E on the beveled face B of the bar as indicated in Fig. 2, the face F of this spacing-pad or projection in the finished bar being parallel to the face C so that when the grate bars are assembled into a grate such as illustrated in Figs. 3 and 4 with the bars lying

side-by-side and drawn together against the spacing-pads or projections E, the bars will all lie in the same plane as indicated in Fig. 4.

From the foregoing it will be seen that the depth of the spacing-pads E depends solely upon the depth of the depressions D so that as distinguished from the present method of manufacturing grate bars the depth of the spacing-pads is practically unlimited, thereby enabling the grate openings, that is to say the spaces G and H, to be of any width desired.

It is to be understood that primarily this invention is directed to the forming of the spacing-pads or projections E and for this reason my invention is not to be limited to first of all rolling the blank into a grizzly shape.

It is to be understood further that the spacing-pads may be of any desired shape, the shape shown in the drawings being merely illustrative.

While the grate bars herein illustrated are straight it is to be understood that they may be made in other shapes within the purview of this invention.

What I claim is:

1. The method of manufacturing a grate bar which method consists in depressing a portion of one face of a blank out of the plane of that face to form a projection or pad on the opposite face.

2. The method of manufacturing a grate bar which method consists in subjecting a blank to pressure to depress a portion of one face of the blank out of the plane of that face and simultaneously form a corresponding projection on the other face of said blank.

3. The method of manufacturing a grate bar which method consists in rolling a blank into a grizzly shape and thereafter depressing a portion of one face of the blank out of the plane of that face to form a projection or pad on the opposite face thereof, the face of which projection is parallel to the face of the blank opposite to the pad.

This specification signed this 2nd day of June, 1920.

WILLIAM A. LEDDELL.
